UNITED STATES PATENT OFFICE.

WILLIAM W. BROWN, OF OAK LANE, PENNSYLVANIA, ASSIGNOR, BY MESNE ASSIGNMENTS, TO H. W. BUTTERWORTH & SONS COMPANY, A CORPORATION OF PENNSYLVANIA.

WRINGER.

Application filed April 26, 1923. Serial No. 634,707.

This invention relates to wringers, and more particularly in some of its more specific details to wringers for wringing clothes or the like, which is especially adapted for employment in connection with washing machines.

It is a general object of the invention to provide an improved wringer construction of the class mentioned which is durable and satisfactory in use, having few parts and being unlikely to get out of order, and being furthermore susceptible of ready assembly or disassembly and repair, and comparatively inexpensive in production costs.

15 A further object of the invention is to provide an improved adjustable releasing mechanism for the rolls of wringers or the like, being adapted to support the rolls securely in desired tension and easily and instantaneously 20 tripped by a convenient arrangement susceptible of easy resetting.

A still further object is the provision of an improved system of drainage for wringers or the like, whereby moisture such as the liquor 25 wrung from the clothes is conducted away into a tub or other convenient receptacle.

Another object is the provision of an improved separable frame construction for wringers or the like, greatly facilitating assembly or disassembly of the wringer and which is light, rigid, and presents a finished 30 external appearance.

Other objects will be in part obvious in connection with the following detailed description of an illustrative but preferred embodiment of the invention, and will be in part 35 pointed out in connection therewith.

This invention accordingly comprises the features of construction, combinations of elements, and arrangement of parts, which will be exemplified in the constructions herein-after set forth and the scope of the application of which will be indicated in the claims.

For a more complete understanding of the 45 nature and objects of the invention, reference is had to the following detailed description and to the accompanying drawings, in which—

Fig. 1 is an end elevation of a wringer constructed in accordance with the invention, the end plate for supporting the driving shaft being removed;

Fig. 2 is a broken top plan view of the same;

Fig. 3 is a vertical transverse sectional view

on the line 3—3 of Fig. 4 looking in the direction of the arrows;

Fig. 4 is a central vertical longitudinal sectional view;

Fig. 5 is a vertical transverse sectional view on the line 5—5 of Fig. 4, looking in the direction of the arrows;

Fig. 6 is a horizontal detail section showing the mounting of the lower roll and the mounting of the front and back drain boards;

Fig. 7 is a section on the line 7—7 of Fig. 3 showing the roll releasing mechanism in plan;

Fig. 8 is a detailed section similar to that of Fig. 3, but showing the roll releasing mechanism in a different position; and

Fig. 9 is a detail view of part of the releasing mechanism.

Referring to the drawing for a detailed description of the embodiment of the invention there illustrated, the wringer includes a frame indicated generally by 10 in which a pair of cooperating parallel rolls 11 are mounted, the lower roll being shown as connected to a driving shaft 12, separably coupled with the roll shaft, and supported in a bracket 13 bolted to the end frame of the wringer. The wringer frame is preferably of metal and made in separable front and back mating sections 14, the sections being similar and detachably secured together as by screws 15. Each of these sections has a lower substantially horizontal base section 16 with upright end sections 17 and 18 disposed at opposite ends of the frame. Both the horizontal and the end frame sections are preferably formed with opposing concavities, and when secured together form a hollow or tubular frame providing a light and rigid construction well adapted for mounting the operative parts of the wringer.

The front and back halves or sections 14 being readily detachable from each other, also provide ready means of disassembly and repair or replacement of parts. As shown in Figs. 6 and 7 the inner wall of the end frame section is provided with inwardly curved opposite extensions 18^a terminating in bulb flanges which rigidify the end frame sections as well as providing end shields for the rolls.

The hollow base section of the frame being disposed longitudinally below the wringer rolls is conveniently utilized as a drain conduit or gutter 19 to conduct away the moisture from the wringer, thus aiding in preventing undue distribution or spattering of the water

and in this manner keeping parts of the wringer and adjacent objects dry. To this end the drain conduit is inclined toward one end of the wringer where a drain opening is provided, being in communication with a swinging drain spout 20. This spout is preferably made in separable halves detachably secured together and is connected with the conduit outlet by a tongue and groove connection 21 to permit swinging adjustment of the spout to discharge as desired into the washer-tub or other adjacent receptacle. In this connection it is noted that the wringer is especially adapted for use in connection with washing machines where the wringer is adapted to swing from one position to another, but it may be used in other relations. The cooperating edges of the wringer sections fit snugly together and may be provided with a packing 20 to secure a liquid tight joint along the conduit 19.

Each frame section is provided with integral supporting brackets 22 and 23 for supporting drain boards 24 preferably pivoted thereto as by pivot screws 25 positioned adjacent to outer edges of the boards so the latter may be swung outwardly. The drain boards may be of wood but are preferably of metal as shown, having smooth upper surfaces across which the clothes pass and are preferably formed with drain openings 26 for carrying away the surface moisture into the drain conduit below. For supporting the drain boards in properly downwardly inclined position with reference to the frame, supporting lugs 27 may be provided on the brackets 23 being adapted to cooperate with lugs or flanges 28 formed on the under side of the drain boards.

Extending between the supporting brackets 22 and 23 and underlying the drain boards are drain tables or plates 29 inclining upwardly from the longitudinal drain conduit being adapted to conduct drippings to the main drain conduit and also functioning as a rigidifying member for the main wringer frame. Thus it will be seen that the main drain conduit has a widely opening upwardly directed mouth well adapted to catch drippings from the wringer rolls, from the clothes as they are approaching the rolls, or from other parts.

The supporting shafts 30 of the rolls extend through medial slots in the inner walls of the end sections of the frame to points within said tubular end sections being supported in bearings 31 housed also in the end sections. Bearings 32 for the shafts are supported by lugs 33 preferably integral with the frame sections and being confined from longitudinal movement by lugs or flanges 34 on one side and the inner wall of the tubular end section on the other side. The upper bearings 31 are similarly confined from longitudinal movement by means of the inner walls of the end sections of the frame and by supporting

and guiding flanges 35, but are supported against roller pressure transversely of the roll shaft by means of adjusting screws 36 and 37. The adjusting screw 37 is preferably mounted in a cap 38 surmounting one of the end sections and detachably secured thereto having its inner end in contact with a metal band or plate on the bearing block to receive tension thrust of the rolls. This adjusting screw is preferably provided with an externally knurled operating knob.

The adjusting screw 36 on the opposite end section of the frame is similarly mounted in a detachable cap 39 surmounting the end section and detachably secured thereto, but in this case the detail construction is modified to furnish a roll release. In this case also the screw engages with a metallic plate on the bearing block 31 but instead of being threaded into the cap as in the case of adjusting screw 37, it is threaded to an abutment block or nut 40 confined for vertical movement in the frame by guiding projections 41 adapted to engage between the flanges 35 and in the slot formed in the inner wall of the end section, as indicated in Figs. 4, 7 and 9. The abutment block 40 is normally held in operative position to receive the thrust of the roll tension when in use by means of a pair of oppositely disposed dogs or detents 42 pivoted to the cap section 39 and normally biased by springs 43, also mounted in the cap section, into position to engage with the abutment block to hold the same securely in position. Each of these dogs is provided with an inwardly projecting arm 44 having curved terminal portions underlying the stem 45 of the knurled operating knob 46. The stem of the operating knob is provided with a square aperture 47 into which the square projection 48 of the adjusting screw 36 is adapted to project, the operating knob being longitudinally slid able upon the square projection. As shown in Fig. 3, normally the locking dogs 42 are held in position by the springs 43 to engage with the upper face of the abutment block and hold the latter in position against upward movement, the screw 36 then being adjustable to apply the required tension on the rolls. Releasing mechanism similar to that described may if desired be employed at both ends of the wringer.

When it is desired to release the roll suddenly, as for example when a heavy clot of clothes is fed into the wringer or the fingers of the operator are accidentally inserted between the rolls, the upper roll may be instantaneously released to upward movement thereof by a downward stroke upon the operating knob 46. This results in throwing the locking dogs 42 outwardly from engaging position with the abutment block, as indicated in Fig. 8, the roll then being free to upward movement. The roll is readily set again for operation by adjusting the abutment block

relatively to the adjusting screw 36, so the locking dogs will move under the influence of their biasing springs into position to engage again the upper faces of the abutment block. Tension may then be applied to the rolls by the adjusting screws as desired.

As shown in Figs. 6 and 7, it will be observed that the laterally projecting flanges 18^a are curved inwardly slightly forming shields for the ends of the rolls so as to guide the advancing clothes into the rolls and prevent them from gaining access to the space between the ends of the rolls and the supporting end frame. Clogging of the clothes into this space will therefore be largely avoided. Furthermore it will be noted that these flanges from smooth evenly curved continuations with the inner surface of the inner wall of the end frame. This smooth continuous surface permits clothes or other matter that may accidentally have gained access to the space between the rolls and the end frame to be readily carried along with the advancing clothes without interference with the operation of the wringer and without injury to the clothes themselves.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a wringer, in combination, complementary front and back frame sections having complementary recesses, said frame sections with their recesses cooperating to form tubular end and base frame elements providing housings in said end elements and a longitudinal conduit in said base element, bearings for the wringer rolls disposed within said housings, cap sections for said frame end elements, means for securing said frame sections in co-operative relationship to form the wringer frame, and adjusting means mounted in said cap sections for adjusting the bearings of one of said rolls.

2. In a wringer, in combination, complementary front and back frame sections co-operating to form housings, cap sections for said frame sections, means for securing said sections in co-operative relationship to form the wringer frame, and adjusting mechanism mounted in said cap sections for adjusting the bearings of one of said rolls, one of said ad-

justing mechanisms including a movable roll supporting member and a pair of releasing dogs pivotally mounted in said cap and cooperating to hold said supporting member in roll supporting position and being movable for releasing the roll independently of adjusting movement thereof.

3. A wringer frame having front and back sections provided with complementary recesses and being detachably secured together to form a rigid hollow frame providing a housing for operative parts of the wringer, cap sections detachably secured in position upon the first mentioned sections, adjusting means for the wringer rolls mounted on one of said cap sections and being disposed within said housing and including an abutment slidably mounted within said housing, and a releasable detent mounted upon the adjacent cap and cooperating to retain said abutment in operative position.

4. A wringer frame having front and back sections detachably secured together to form a rigid hollow frame providing a housing for operative parts of the wringer, said sections having complementary concavities co-operating to form a drain conduit in the lower part of the frame.

5. A wringer having front and back frame sections detachably secured together to form a rigid hollow frame providing a housing for operative parts of the wringer, bearings for the wringer rolls housed within said frame, and lugs on said frame sections for supporting and confining said bearings, said sections having complementary concavities co-operating to form a drain conduit in the lower part of the frame.

6. A wringer having front and back frame sections detachably secured together to form a rigid hollow frame providing a housing for operative parts of the wringer, said sections having complementary concavities co-operating to form a drain conduit in the lower part of the frame, and a detachable drain spout swivelled to said frame and communicating with said conduit.

7. A wringer having front and back frame sections detachably secured together, said frame sections including substantially horizontal sections co-operating to form a hollow base for the wringer frame serving as a drain conduit underlying the wringer rolls, and upright members co-operating to form hollow ends of the wringer frame and to house operative parts of the wringer.

8. A wringer having front and back frame sections detachably secured together, said frame sections including substantially horizontal sections co-operating to form a hollow base for the wringer frame serving as a drain conduit, upright members co-operating to form hollow ends of the wringer frame and to house operative parts of the wringer, and a drain spout communicating with said con-

duit and comprising a plurality of separable sections secured together and interlocking with said frame so as to swing thereon in a horizontal plane.

5 9. A wringer frame having front and back
frame sections detachably secured together
to form a hollow frame providing a housing
for operative parts of the wringer, a drain
table on one of said sections outwardly dis-
10 posed therefrom and inclined toward the
wringing frame, and a perforated drain board
overlying said drain table.

10. A wringer having front and back frame sections detachably secured together to form
15 a hollow frame providing a housing for operative parts of the wringer, said sections co-operating to form a drain conduit in the lower part of the frame, a drain table on one of said sections outwardly disposed therefrom and inclined to drain toward said drain conduit, and a drain board overlying said drain table.

11. A wringer having front and back frame sections detachably secured together to form a hollow frame providing a housing for operative parts of the wringer, said sections co-operating to form a drain conduit in the lower part of the frame, a drain table on one of said sections outwardly disposed therefrom and inclined to drain toward said drain conduit, and a drain board overlying said drain table, said drain board inclining away from the wringer and having openings therein so moisture may pass therethrough over said drain table into the drain conduit.

12. A wringer frame having front and back sections detachably secured together to form a tubular frame providing a housing for operative parts of the wringer, said frame including a lower horizontal and upright tubular parts, said horizontal frame part forming a drain conduit disposed beneath the wringer rolls and having oppositely disposed upwardly and outwardly flaring plates forming drain tables sloping into said drain conduit.

13. A wringer frame having front and back frame sections detachably secured together to form a tubular frame providing a housing for operative parts of the wringer, said frame including a lower horizontal and upright tubular parts, said horizontal frame part forming a drain conduit disposed beneath the wringer rolls and having oppositely disposed upwardly and outwardly flaring plates forming drain tables sloping into said drain conduit, and a perforated drain board overlying said drain table and extending between the roll and the outer part of said drain table.

60 14. In a wringer, in combination, a frame, rolls mounted in said frame, means for adjusting the tension between said rolls, said means including an abutment block, a rod adjustably co-operating with said block, a handle for effecting adjustment between said block

65

and rod and being movable independently of said rod; means for supporting said block in operative position, and means controlled by movement of said handle independently of rod movement for withdrawing said supporting means and thereby releasing the tension on the rolls. 70

15. In a wringer, in combination, a frame, rolls mounted in said frame, means for adjusting the tension between said rolls, said means including an abutment block, a rod adjustably cooperating with said block, a handle for effecting adjustment between said block and rod; dogs pivotally mounted on the wringer frame and being adapted to support said block in operative position, and means controlled by said handle for operating said dogs to release tension on the rolls. 75 80

16. In a wringer, in combination, a frame, rolls mounted in said frame, means for adjusting the tension between said rolls, said means including an abutment block, a rod adjustably co-operating with said block, a handle for effecting adjustment between said block and rod; dogs pivotally mounted on the wringer frame and being adapted to support said block in operative position, and means controlled by said handle for operating said dogs to release tension on the rolls, said dogs being biased to reengage with said block when the latter is adjusted. 85 90 95 99 105

17. In a wringer, in combination, a frame, rolls mounted in said frame, means for adjusting the tension between said rolls, said means including an abutment block, a rod adjustably co-operating with said block, a handle for effecting adjustment between said block and rod; means for supporting said block in operative position, and means controlled by said handle for withdrawing said supporting means and thereby releasing the tension on the rolls, said block supporting means being biased to reengage with said block when the latter is readjusted.

18. In a roll releasing mechanism, in combination, a threaded abutment block, a threaded rod engaging the threads of said block and co-operating with the roll to support the same in operative position, supporting dogs adapted to co-operate with said block to support it in roll holding position, and means for releasing said dogs. 110 115

19. A roll releasing mechanism, in combination, a threaded abutment block, a threaded rod engaging the threads of said abutment block and co-operating with the roll to support the same in operative position, an operating knob for said rod mounted for movement thereon, supporting dogs adapted to co-operate with said block to support it in roll holding position, said knob being operable to release said dogs from holding position.

20. In a roll releasing mechanism for wringers, in combination, a wringer frame in- 130

cluding a detachable cap section, a roll support, a roll supporting abutment block slidably mounted in said frame, roll supporting dogs mounted in said cap being removable 5 therewith away from said abutment block and adapted to hold said abutment block in roll supporting position, and means for releasing said supporting dogs.

21. In a roll releasing mechanism, in combination, a movably mounted abutment block, a rod adjustably engaging said block and cooperating with the roll to support the same in operative position, pivoted detents having arms engaging said abutment block to support the latter in roll supporting position, and an operating member cooperating for adjustment of said rod and to release said detents from holding position.

22. A wringer frame having a tubular end

section forming a housing for operating parts 20 of the wringer, and a laterally extending flange adjacent the inner wall of said end section forming a shield to avoid entry of material between the roll and frame and forming with said inner wall a smooth continuous surface opposing the rolls so as to permit easy passage of any material which may have found its way into the space between the rolls and wringer frame.

23. A wringer frame having a tubular end 30 section provided with upright laterally extending rigidifying flanges adjacent to and forming substantially continuations of the inner wall of said end sections and also forming shields adjacent the front and rear sides 35 of the ends of the wringer rolls.

In testimony whereof I affix my signature.
WILLIAM W. BROWN.
